SAFETY DEVICE FOR GAS RANGES

Augustine L. N. Fleming, Rutherford, N. J.

Application February 8, 1934, Serial No. 710,250

2 Claims. (Cl. 126—42)

The purpose of this invention is to provide means for automatically closing all of the valves to the burners of a gas range by a common latch or, as in a covered range, as the cover is closed. 5 The invention is an attachment that may be built into a gas range or attached to gas ranges now in use which permits the valves to be opened or closed independently, and at the same time automatically closes all the valves from a common point. Gas ranges are now being built with covers which cover and enclose the burners and it is possible to close the cover without turning off the burners. It is also possible to accidentally open one or more of the valves and with the cover closed it is impossible to detect the gas so that it is very dangerous. With some of the types of open gas ranges where the valves are provided with round discs and handles it is also practically impossible to determine whether or not the gas 10 is turned on without actually trying each handle.

The object of this invention is, therefore, to make it impossible to close the cover of a covered gas range without turning off all of the valves.

Another object is to provide means for automatically turning off all the valves when the cover is closed.

Another object is to provide means for turning off all of the burners of a gas range from a common point.

30 Another object is to provide means for turning off the burners of a gas range and locking the valves thereof in the closed position.

And a still further object is to provide means for automatically turning off all the burners of 35 a gas range which is of a simple and economical construction.

With these ends in view the invention embodies a device for turning off the burners of a gas range which may be mounted upon or attached to a 40 gas range of any type so that it will turn off the valves as the cover of the range is closed, or from a common point.

Other features and advantages of the invention will appear from the following description 45 taken in connection with the drawing, wherein:

Figure 1 is a plan view showing the general arrangement of the apparatus on a gas range.

Figure 2 is a view showing a front elevation of the upper part of the range showing the device 50 mounted thereon.

Figure 3 is a view showing a side elevation of the upper part of the range showing the method of connecting the device to the cover of the range.

Figure 4 is a view looking toward the inside 55 of one of the burner valve operating knobs.

Figure 5 is a view looking toward the side of one of the knobs showing the jaw clutch members extending therefrom.

Figure 6 is a view similar to that shown in Figure 2 showing an alternate arrangement in which 5 a closure latch is provided which may be used for ranges without covers.

In the drawing the invention is shown as it may be made wherein numeral 1 indicates an operating bar, numeral 2 the valves of a gas 10 range, and numeral 3 a cover for the range.

It will be understood that the valves 2 and the range may be of any type or design and the range may be provided with a cover, as shown in Figure 3, or of any type or design. 15

In the design shown the bar 1 is positioned below the valves 2 and a jaw clutch is positioned on the valve stems with one section of the jaw teeth formed at the handles or knobs 4 on the valve stems and the teeth of the other section 20 formed in a hub 5 and the hub 5 is provided with an arm 6 which extends downward and which is pivotally connected to the bar 1 by pin 7. Altho this construction is described for one of the valves, it will be understood that the same members are 25 used with each of the valves and as many valves as there are burners may be provided and all may be similarly connected to the bar 1. The bar 1 is connected by rod 8 to a bell-crank 9 which is pivotally mounted on a pin 10 and the 30 opposite end of the bell-crank is connected by a rod 11 to an arm 12 extending downward from the rear corner of the cover 3, as shown in Figure 3. It will be understood, however, that the arm 12 may also be provided on a separate hub 35 13, as shown in Figure 1, and mounted upon a shaft 14 upon which the cover 3 is pivotally mounted and the arm may also be located or positioned at any point. It will also be understood 40 that any other means may be used for connecting the cover 3 to the bar 1 and the connecting parts may be located at any point or points.

This rod may also be operated by a handle 15, as shown in Figure 6, in which it is connected to the handle by a rod 16 and when a pointer 45 17 on the handle registers with the word closed all of the valves are in the closed position so that, with a gas range of an open type, it is only necessary to turn the handle 15 in order to be assured 50 that all of the valves are closed. It will be understood, however, that any other means may be used for closing all of the valves independently or in combination, and any other means may be used for indicating when the valves are closed.

It will be noted in Figure 4 that the handles 55

18 of the valves, on the face of which the hubs 4 are located, are provided with teeth 19 and 20 which may be located as indicated by the vertical lines, and the hubs 5 may be provided with teeth 21 and 22 as indicated by the horizontal lines, and when the cover is in the closed position the teeth will be in the position shown in the Figure 4, however, when the cover of the range is opened the teeth 21 and 22 will travel thru an arc of 10 ninety degrees so that they will be in the position indicated by the curved lines 23. The handles 18 are then free so that they may be turned from the position shown to the position indicated by the diagonal lines 24 so that the valves may be 15 opened, however, should the cover be closed, the teeth 21 and 22 will return to the positions as indicated, and thereby return the teeth 19 and 20 to their respective positions, as indicated, thereby closing the valve. It will, therefore, be 20 observed that this device permits the valves of each burner to operate independently and at the same time closes any one or all of the valves, and holds all of them in the closed position, as long as the cover is closed, or when the handle 15 is 25 turned to the closed position. It will also be understood that the jaw clutches may be replaced by any other means for producing this action and the teeth of the clutch may be of any other type or design.

30 It will be understood that other changes may be made in the construction without departing from the spirit of the invention. One of which changes may be in the use of other means for connecting the bar 1 to the valves, another may 35 be in the use of other means for operating the valves instead of the jaw clutches, as shown, another may be in the use of other means for connecting the valve closing means to the cover or member 15, and still another may be in the use of the closing apparatus located at any other 40 point or points.

45 The construction will be readily understood from the foregoing description. In use this device may be provided as shown and described and it will be noted that the ordinary valve operating handles or levers may readily be removed and replaced by similar handles having jaw teeth in the hubs thereof, or the teeth may be formed or attached to the present handles in any other manner. The hubs 5 are placed on the valve 50 stems before the handles are returned, and these may readily be connected to the cover thru the bar 1 and operating levers, as shown and de-

scribed. It will, therefore, be observed that this device will automatically close or turn off all the burners of a gas range from a common point or as a cover of the range is closed and this device will also hold and lock all of the burners in the 5 closed position. It will be noted that the connecting means may be of any other type or design and may be positioned, arranged, or located in any position. It may also be used with one or any number of burners and the burners may be 10 located at any point or points.

Having thus fully described the invention what I claim as new and desire to secure by Letters Patent, is:

1. The combination with a gas range of the 15 type having a plurality of burners with individual valves for the respective burners, and valve handles on the ends of the valve stems extending from the valves; of clutch members on said valve handles with projections extending therefrom, 20 corresponding clutch members rotatably mounted on said valve stems provided with projections positioned to engage with the projections of the clutch members on the handles, arms extending from the clutch members on the valve stems, a 25 bar pivotally attached to said arms, and means for moving said bar, the set of projections on the clutch members of the stems positioned to engage the set of projections on the clutch members of the handles to move the valves through 30 the handles to closed position in one position of the bar, and in another position of the bar to allow the valve handles to be operated independently of the projections on the clutch members on the valve stems. 35

2. The combination with a device as described in claim 1, in which said means for moving said bar comprises a bell crank pivotally mounted on the range, means connecting one end of said bell crank to the operating bar pivotally 40 attached to the arms of the clutch members on the valve stems, a burner top cover pivotally mounted on the rear edge of said range, a lever positioned at the back of said cover and adapted to be rotated with the movement of the cover, 45 and a rod connecting said lever to the bell crank, said lever adapted to move the bell crank to move the bar, and move the projections of the clutch members on the valve stems to engage the projections of the clutch members on the handles to 50 close the valves as the cover of the range is lowered.

AUGUSTINE L. N. FLEMING.
